[57] ABSTRACT

An improved pressure loaded pump having a flat sealing plate in the gear cavity with a face spaced from a parallel end face of the housing. A land member extends axially between the plate and housing in this area to surround the inlet and shaft openings on the plate and to define a pressure loading chamber. A seal pack in the chamber seals against the land member and one of the parallel seal plate and housing faces to separate the chamber from the inlet and shaft openings. The seal pack, in itself, further defines zones of pressure on the seal plate maintained at pressures different from that in the chamber.

PRESSURE LOADED GEAR PUMP

BACKGROUND OF THE INVENTION

This invention relates to positive displacement hydraulic gear devices of the type incorporating pressure loaded side sealing plates. More particularly, the invention relates to improved sealing means contained wholly within the gear cavity effecting fluid sealing of the transverse gear faces.

Devices of the class described generally incorporate a movable sealing plate arranged such that one side is pressed upon the transverse gear faces to seal same. One or more pressure chambers, fed with fluid from the device, on the opposite side of the plate urge the plate toward the gears. Such chambers and the means required to seal the chambers have generally produced complicated and expensive design of the sealing plate, the housing and other components. In particular, prior art designs contemplate grooves in either the seal plate or the housing to carry the sealing means delimiting and defining the radial limits of the pressure chamber.

SUMMARY OF THE INVENTION

The present invention proposes improved sealing means providing pressure loaded sealing of the gear side faces distinctly simpler and more economical than prior art. Yet, the invention also creates precise side loading and optimal pump efficiency. It is particularly characterized by a lack of grooves in the seal plate and housings for delimiting the pressure chamber. Instead, the device of the present invention utilizes sealing means freely positioned within the pressure chamber.

The invention contemplates a flat sealing plate movably disposed within the gear cavity with one side adjacent the gear side faces and the outer face spaced from a parallel face of the gear housing. A rigid land member, integral with one of the parallel sealing plate and housing faces, protrudes axially toward the other of the parallel faces. This land member partially surrounds the fluid inlet and shaft areas of the device which are maintained at relatively low pressures. The land wall, along with the gear cavity wall, form the boundaries of a pressure loading chamber in the space between the parallel sealing plate and housing faces which is in communication with pressure fluid from the fluid outlet. The chamber covers an area of the sealing plate face so as to create sufficient force to urge the plate into light sealing engagement with the lateral faces of the gears. A three-element seal pack, disposed within the pressure chamber, seals against one of the parallel faces and at right angles against the land to isolate the pressure chamber from the lower pressure inlet and shaft areas. The seal pack itself defines a fluid zone within the main pressure chamber which is isolated therefrom and maintained at a pressure somewhat less than that of the main pressure chamber. The invention thus provides a pressure loading chamber of desired design with separate pressure zones without introducing complicated design of the seal plate or housing.

The invention, therefore, generally contemplates improved side sealing means for hydraulic gear devices simple and economical in design.

The invention has a primary objective of providing a sealing plate for engagement with the gears in a rotary fluid machine having a pressure loaded rear surface spaced from a parallel housing surface with land means projecting axially therebetween to define a pressure

loading chamber and to surround areas of pressure different from that of the loading chamber. Sealing means positioned at right angles against the land and one of the parallel faces isolate and seal the pressure loading chamber from the areas maintained at different pressure.

A further object is to provide improved sealing means for devices constructed in accordance with the preceding objective.

Yet another object is to provide such sealing means which define a zone wholly confined within the sealing means hydraulically isolated from the main pressure loading chamber and maintained at a pressure different from that of the main chamber.

These and other objectives and advantages of the present invention are specifically set forth in or will become apparent from the following detailed description and accompanying drawings of a preferred embodiment of the invention.

BRIEF DESCRIPTION OF THE

In the drawings:

FIG. 1 is a transverse section of a gear pump embodying the present invention;

FIG. 2 is a view taken along line 2-2 of FIG. 1;

FIG. 3 is a view taken along line 3-3 of FIG. 1 showing the seal plate face 43 which engages the sides of the gears;

FIG. 4 is a view taken along line 4-4 of FIG. 1 showing the opposite pressure loading side 44 of the seal plate;

FIG. 5 is an exploded perspective view of the seal plate and the three elements of seal pack 51;

FIG. 6 is a view taken along line 6-6 of FIG. 4;

FIG. 7 is a view taken along line 7-7 of FIG. 4; and

FIG. 8 is a view taken along line 8-8 of FIG. 4.

DESCRIPTION OF THE PREFERRED EMBODIMENT

The gear device in FIG. 1, designated generally by the numeral 20, has a housing including end plates 21 and 22 and a body 23 sandwiched between and secured to the plates 21, 22. A gear cavity 24 within the body, shown in FIG. 2, accepts a pair of intermeshing gears 25, 26 whose teeth tips closely fit the cavity wall 27. Each gear is affixed to a shaft 28, 29 that is mounted for rotation within bushings 30 provided in shaft bores in the end plates. A fluid inlet 31 and outlet 32 open into opposite sides of cavity 24 and communicate with external ports in the housing for delivery and discharge of fluid.

In the following description of operation, the unit will be considered as a pump though it is equally useful as a motor. Upon rotation of shaft 28 by an external engine, gear 25 drives gear 26, and fluid drawn in through inlet 31 is trapped in the intertooth gear spaces and transported around the cavity wall 27 to high pressure outlet 32. While traveling around the periphery of the gear cavity from inlet to outlet, pressure of the intertooth spaces gradually increases, this pressure increase with rotation generally being referred to as the pump pressure gradient. The pressure gradient zone of the pump denotes those portions subject to pressure which are intermediate inlet and outlet pressure. As the gear teeth engage in the central mesh area 33, fluid displaces and discharges through the outlet. The higher pressure at the outlet side urges the gears leftwardly in

60
65

FIG. 2 so that the gear teeth tips seal against cavity wall 27 near the inlet to prevent efficiency reducing reverse flow from outlet to inlet around the gear periphery. The gears themselves effectively prevent leakage flow from outlet side 32 to inlet side 31 through mesh area 33. The gear transverse faces 34 lightly press and seal against end plate 21, and an axially movable seal plate 36 disposed within the gear cavity 24 between gear faces 35 and flat face 45 of end plate 22 seals transverse face 35. Fluid pressure between the seal plate and end plate urges seal plate 36 and the gears leftwardly in FIG. 1 to effect sealing of the transverse gear faces.

As best seen in FIGS. 3 and 4, the outer periphery of seal plate 36 closely fits cavity wall 27 about a substantial arc from the inlet 31 around each gear. Side 43 of the seal plate 36 is a flat surface of bearing quality material that sealingly contacts gear faces 35. Reliefs 37, 38 in the periphery of the plate adjacent the inlet and outlet respectively, interconnect the gear teeth pockets with inlet or outlet to equalize pressure therewith as those pockets near inlet or outlet during gear rotation. Central openings 39, 40 accept the shafts, and a generally circular depression 41 surrounds each opening as shown in FIG. 3. Another recess 42 protrudes radially from each depression 41 past the gear root circle to communicate with the gear teeth pockets to feed pressure fluid to openings 39, 40 for lubrication of the shaft bushings. Recesses 42, positioned a short arc distance from relief 37, direct fairly low pressure fluid to the bushings as they pick up fluid at a lower pressure point in the pump pressure gradient zone. To those skilled in the art, it will be apparent that pressure at a certain location in the pressure gradient zone, such as at depression 42, varies markedly with changes in different operating parameters such as speed of gear rotation and outlet pressure. Pressure in the bearing openings accordingly may vary from near inlet pressure to outlet pressure with changes in the operating parameters. Bearing pressure may be controlled if desired by, for instance, including a pressure relief valve in the bearing pressure area.

The opposite face 44 of the seal plate extends in close association with end face 45. FIG. 4 illustrates seal plate face 44 and the upstanding land member 46 formed integrally with seal plate 36 upon face 44 and extending axially thereof toward end plate face 45. Land 46 surrounds each shaft opening 39, 40 and has a portion 47 substantially surrounding the inlet by extending between the shaft openings and from each opening 39, 40 laterally to the cavity wall 27. Note that in this embodiment a seal receiving groove 70 in portion 47 extends around inlet 31 and opens at the cavity wall 27 on opposite sides of the inlet. As can be seen both in FIGS. 3 and 4, the sealing plate has through oblong slots 48 permitting communication of fluid in the intertooth pockets with face 44 as the pockets pass slots 48.

The outward edge 49 of land 46 forms, along with a portion of cavity wall 27, the periphery of a fluid chamber 50 laterally bounded by the parallel spaced faces 44 and 45 of the sealing plate and end plate. A portion of chamber 50 is occupied by a seal pack assembly 51 which will be described in greater detail below. Pressure fluid is communicated to chamber 50 via the seal plate peripheral relief 38. Chamber 50 extends from gear cavity wall 27 radially inwardly past the gear root circle at the bottom of the gear teeth pockets, and ex-

tends circumferentially around the gears from the outlet to points adjacent the inlet and includes areas of surface 44 opposite areas of face 43 exposed to pressure less than outlet pressure. Outlet pressure in chamber 50 will therefore overbalance the lower pressures adjacent the inlet and inside the gear root circle to push plate 36 against the gears. In particular, the plate 36 is overbalanced and pressed into sealing engagement at those areas where sealing is most required, in the pressure gradient zone and around the shaft openings 39 and 40.

For effective operation it will be apparent that chamber 50 must be sealed from the lower pressure shaft openings 39, 40 and inlet 31 in order to maintain the higher outlet pressure in chamber 50 and to minimize inefficient fluid leakage from chamber 50. The sealing plate itself provides a portion of this chamber 50 sealing by its peripheral contact with cavity wall 27 and by its physical separation of chamber 50 from the gear cavity proper. Positioned within chamber 50 and supported by land 46, the seal pack 51 seals against its edge 49 and against end plate face 45 to separate chamber 50 from shaft openings 39, 40 and inlet 31.

FIG. 5 illustrates the three, generally 3-shaped elements 52, 53, 54 comprising the seal pack, that, as seen in FIGS. 1 and 6, assemble upon seal plate face 44. Thin protector gasket 52, of nylon or other extrusion-resistant material, is of a U-shaped cross-section with its bottom face 55 lying directly upon seal plate face 44 and its legs 56, 57 extending axially toward end plate face 45. At its ends, gasket 52 has a continuous inner wall 58 surrounding a through opening in the gasket.

The elastomer o-ring 53 is an endless pliable element of generally circular cross-section which is doubled and positioned within the protector gasket 52 in the same characteristic "3" form. O-ring 53 loops around gasket inner wall 58 at each end and creates a double strand running the remainder of the length of the protector gasket. FIGS. 6 and 7 clearly show how the o-ring fits within gasket 52 at inner wall 58 and at other positions. Elastomers of a variety of cross-sections may be utilized; the o-ring is chosen in the present embodiment due to its availability and economy. Alternately, the elastomer can be integrally formed as a single element with eyelets at either end looping walls 58.

The third seal element is a generally U-shaped back-up gasket 54 made of relatively rigid fibrous material and generally conforming in size and shape to the portion of seal flat face 44 forming the lateral face of pressure chamber 50. As seen in FIG. 6, the protector gasket legs 56, 57 fit within depending back-up gasket legs 59, 60 to enclose a rectangular space containing elastomer 53. Upper surface 61 of back-up gasket 54 sealingly engages end plate face 45, and side face 62 seals against wall 49 of land 46. Gasket 54 thus provides two right angle faces 61, 62 which effectively seal chamber 50 from the lower pressure inlet and shaft openings. At its ends, as seen both in FIGS. 5 and 7, back-up gasket 54 has an island projection 63 snugly protruding inside protector gasket wall 58. In this area, the outer back-up gasket leg 59 is deleted and protector gasket wall 56 engages gear cavity wall 27.

The protector gasket inner wall 58 and back-up gasket island 63 cooperate to form a separate pressure chamber 64 within but isolated from the pressure chamber 50. Slot opening 48 feeds intermediate pressure fluid from the pressure gradient area of the gear cavity to chamber 64 which is accordingly maintained

at a pressure lower than the outlet pressure in chamber 50. Chamber 64 is outlined by dashed lines in FIG. 4 to clearly show that portion of sealing plate face 44 subject to the intermediate pressure. These portions extend over a considerable area opposite the pressure gradient zones within the gear cavity. The use of staged or intermediate pressure chambers provides a more precise balance of seal plate 36 such that it lightly and uniformly presses upon the transverse gear faces without creating unnecessarily high friction over a wide range of operating conditions. The uniform balance prevents disastrous cocking of the seal plate against the gear faces. The utility of intermediate pressure chambers is well known in the art and a more complete description may be found in U.S. Pat. No. 2,809,592 of Wendell E. Miller and Leonard H. Reimer. The efficacy of such staged pressure chambers relates directly to the size of the gear pump; a large gear pump which has a greater extent of pressure gradient area has far greater need of intermediate pressure loading chambers than do small pumps. Larger displacement pumps may require a plurality of staged zones at distinct pressures.

Chamber 64 communicates through bore 65 with recess 66 in the face 61 of gasket 54. Recess 66 is substantially equal to chamber 64 in area to assure a pressure balance across island 63 and prevent the accumulation of higher discharge pressure in recess 66 which would, under certain conditions, increase the pressure in chamber 64 to discharge pressure.

By forming chamber 64 entirely by and within the seal pack elements, design of seal plate 36 and end plate face 45 are simplified, thereby reducing costs while increasing unit reliability and life. Assembly procedures are also considerably simplified. In contrast, prior art pumps normally create an intermediate pressure chamber by an island such as 63 integrally formed upon either the seal plate or end plate and a complex groove system surrounding the island and carrying fluid seals.

As discussed, back-up gasket 54 serves primarily to seal at right angles against edge 49 of land 46 and the end plate face 45. Protector gasket 52 assists in sealing but serves primarily to prevent extrusion of "flowing" of the soft o-ring 53 from its proper position. High pressure differentials across a soft element such as an o-ring member can destroy the member by forcing it to extrude to the lower pressure areas unless protected by a non-extruding element such as gasket 52.

O-ring 53 primarily seals the intermediate pressure chambers 64. The o-ring also forms a trough 67 intermediate its double strand and seals this trough from the discharge pressure of chamber 50. Trough 67, shown in dotted lines in FIG. 4, is not sealed from the intermediate chambers 64 and normally carries chamber 64 pressure by communicating therewith between walls 58 and islands 63. This trough, along with chamber 64 at intermediate pressure, adds with the higher discharge pressure across the remainder of face 44 to produce a precise force slightly and uniformly overbalancing the gear cavity forces to urge the seal plate into light, but sealing contact with gear faces. The o-ring also initially compresses axially to provide slight preloading to hold gaskets 52 and 54 against faces 44 and 45.

For clarity the relative proportions of the sealing elements have been somewhat distorted in FIGS. 6-8. Elastomer 53 compresses axially but not laterally. In

certain circumstances it has been found advantageous to induce lateral compressing of the left strand of o-ring 53 in FIG. 7 between body 23 and island 58, and in other applications it may be desirable to include lateral compression of the elastomer.

The utilization of an intermediate chamber 64 is optional, being dependent upon the overall size of the pump. Without such chamber the design and elements of the seal pack may be varied considerably, subject to the primary requirement that the seal pack effect right angle sealing against the end plate face and the support wall to isolate pressure chamber 50 from the inlet and the shaft openings.

The design of seal pack 51 is such that it can be freely positioned in the pressure chamber 50 and need not be confined within a groove in the seal plate 36 or end plate 22. Pressure in chamber 50 urges the seal pack against land edge 49 and end plate face 45 and holds the seal pack in proper sealing position. Fluid flow patterns set up in chamber 50 will not move or "wash out" the seal pack due to the relatively rigid nature of the outer sides of the seal pack, especially leg 59 of gasket 54 which is laterally unsupported over an extensive area and particularly unsupported at peripheral relief 38. In contrast, prior art designs incorporate the sealing means in a groove to give the required lateral support. Being freely positioned in pressure chamber 50 also distinctly simplifies assembly of the seal pack into the unit.

Sealing groove 70 in the inlet portion 47 of support 46 accepts an o-ring 71, L-shaped back-up gasket 72 and protector gasket 73, illustrated in cross-section in FIG. 8. The back-up gasket 72 along with o-ring 71 effect the primary sealing against end plate face 45 and the wall 74 of groove 70 adjacent the inlet 31. This seals against fluid leakage from the higher pressure shaft openings to inlet 31 and prevents loss of bearing lubrication fluid. Protector gasket 73, like gasket 52, prevents extrusion of o-ring 71.

The specific embodiment described utilizes a support member 46 integral with the seal plate and a seal pack disposed to seal against the end plate. It will be quite apparent that such arrangement can be reversed with the land member made integral with the end plate and the seal pack sealing against seal plate face 44. As noted above, the present invention also contemplates variations in designs of the seal pack, for instance, deletion of the intermediate pressure chamber 64. To the extent that these and other variations and changes do not depart from the scope and spirit of the invention as set forth in the appended claims, they are intended to be included within same.

Having described our invention with sufficient clarity such that those skilled in the art may construct, use and practice it, we claim:

1. In an axially pressure loaded gear pump having a housing enclosing an internal gear cavity having fluid inlet and outlet means opening into opposite sides of the cavity; a pair of intermeshing gears having transverse gear faces disposed in the cavity and affixed to axially extending shafts rotatively mounted in the housing; an axially movable seal plate disposed entirely within said cavity having one side in sealing engagement with the transverse gear faces and an opposite flat face disposed parallel and spaced from a transverse end face of the gear cavity to define a space therebetween,

said plate having bores accepting the shafts, wherein the improvement comprises:

a land member integral with said seal plate extending axially between said parallel faces and occupying only that portion of said space between the parallel faces surrounding the inlet and shaft bores, said land member and the wall of said cavity defining a pressure chamber of substantially uniform axial width in the remainder of said space; 5 means communicating outlet pressure to said pressure chamber to urge said plate toward the gears; a first relatively rigid U-shaped gasket member in said chamber having a base and a pair of axially extending legs depending from the base, pressure in said chamber urging one of said legs and said base respectively into sealing engagement with said land member and said gear cavity end face to seal said chamber from said inlet and said shaft bores, said one leg of the gasket being laterally supported by said land member while the other leg of said gasket is laterally unsupported against said pressure in the chamber; 10 a resilient endless o-ring positioned within said U-shaped gasket member; a second gasket in said pressure chamber cooperat- 15 ing with said first gasket and o-ring to form a zone within and isolated from said pressure chamber; and an aperture in said seal plate directing pressure to said zone lower than pressure in said chamber. 20

2. In an axially pressure loaded gear pump having an axially movable side sealing plate wholly contained within the rotor cavity of the pump housing, the rear face of said sealing plate and the adjacent housing end wall comprising the transverse faces of a fluid pressure chamber therebetween of substantially uniform axial width, said sealing plate and housing defining inner and outer axially extending radial walls of said chamber; 25 improved means for sealing said chamber, comprising: first and second gaskets disposed wholly within said chamber and cooperating with each other to define an enclosed space therebetween, said first gasket having adjacent right angle faces urged by chamber pressure into sealing engagement with one of said chamber transverse faces and said inner wall of said chamber; 30 said second gasket having a base urged by chamber pressure into sealing engagement with the other of said chamber transverse faces; and a resilient elastomer positioned in said space and 35 compressed between said gaskets so as to urge same initially against said chamber transverse faces. 40

3. In a hydraulic gear device having a housing enclosing an internal gear cavity having spaced apart end walls, fluid inlet and outlet means opening into opposite sides of the cavity; a pair of intermeshing gears disposed in said cavity between said end walls and closely fitting the cavity confines and presenting a transverse side spaced from an adjacent one of said end walls of the cavity; axially extending shafts in the housing rotatively supporting each gear whereby upon rotation said gears carry fluid from the inlet to the outlet; wherein the improvement comprises:

a unitary fluid sealing plate movably disposed within said gear cavity intermediate said transverse side of the gears and said adjacent end wall, said sealing

plate having one side in sealing engagement with said transverse side of the gears and an opposing face arranged parallel and spaced from said adjacent end wall defining a space therebetween; a land member disposed within said space and extensive through only that portion of said space which surrounds said shaft openings and the inlet, said land member engaging the edge of said gear cavity adjacent the inlet, whereby said land member and said gear cavity edge define a pressure chamber of substantially uniform axial width in the remaining portion of said space between said adjacent end wall and said opposing face of the sealing plate; sealing means movably disposed wholly within said pressure chamber and conforming generally in shape to the edge of the land member; and means communicating said pressure chamber with said outlet whereby pressure from said outlet biases said sealing plate against said transverse side of the gears and urges said sealing means axially into opposite sealing engagement with said adjacent end wall and said opposing face of the sealing plate and transversely into sealing engagement with said land member to seal said pressure chamber from said shaft openings and said inlet, said sealing means including a first U-shaped gasket with a pair of parallel legs extending perpendicularly and axially from a bottom face which is adjacent said adjacent end wall, said chamber pressure urging said bottom face axially against said adjacent end wall and urging one of said perpendicular axial legs transversely against said edge of the land member.

4. The device of claim 1 further including a groove in said land member, and second sealing means in said groove preventing fluid flow across said land member between said shaft openings and the inlet.

5. The device of claim 1 wherein said sealing means further includes resilient means contained within said U-shaped first gasket and axially compressed between said sealing plate and adjacent end wall.

6. The device of claim 5 wherein said sealing means includes a second U-shaped gasket having a bottom face lying upon said sealing plate and having parallel legs axially extending within said first gasket legs, said first and second gaskets forming therebetween a rectangular trough containing said resilient means.

7. The device of claim 6 wherein said resilient means comprise an endless elastomer o-ring located in said trough and surrounded by said gaskets.

8. In an axially pressure loaded gear pump having a pair of intermeshing gears journaled upon axially extending shafts and located within a housing pumping cavity, a flat sealing plate in the housing cavity with one face in sealing engagement with the transverse gear faces and an opposite face parallel to and spaced from a transverse end face of the housing cavity, and a rigid land member on said sealing plate extending axially in said space between the sealing plate and housing end plate to define a pressure loading chamber of substantially uniform axial width in said space fed with outlet pressure fluid; improved means for sealing said chamber comprising:

a first U-shaped gasket having a back face with leg members depending at generally right angles thereto, said gasket disposed in said chamber having said back face and a leg member urged by pres-

sure in said chamber into sealing engagement at right angles with said land member and said end plate;
a second U-shaped gasket inverted with respect to said first gasket and radially confined within the legs of said first gasket and having a bottom face lying upon the sealing plate to define a rectangular space between said gaskets; and
a resilient elastomer member located inside said gaskets in said rectangular space, said elastomer being compressed axially to initially preload said first and second gaskets against said end plate and sealing plate faces respectively.

9. The device of claim 8 wherein said resilient elastomer is an endless elastomer o-ring arranged to form a double strand in said rectangular space.

10. The device of claim 9 wherein said second gasket is provided with interior walls extending into said rectangular space defining openings in said bottom face registering with corresponding conduits in said seal plate which communicate with pressure developed in the gear cavity intermediate inlet and outlet pressure, said first gasket having an island portion at each end adapted to be received within said interior walls to define intermediate pressure zones between each of said islands and the sealing plate, said o-ring sealing against said interior walls to separate said zones from the pressure chamber.

11. An axially pressure loaded positive displacement gear pump comprising:

a housing enclosing an internal gear cavity and having spaced apart transverse end faces;
fluid inlet and outlet means opening into opposite sides of said cavity;
a pair of intermeshing gears in said cavity affixed to axially extending shafts journalled in the housing, said gear peripheries closely fitting the wall of said cavity such that the gears receive low pressure fluid from the inlet and deliver higher pressure fluid at the outlet, said gears having transverse faces spaced from an adjacent end face of said housing;

a sealing plate movably disposed in said cavity with one side in sealing engagement with the transverse gears faces and an opposite flat face parallel and spaced from said adjacent housing end face to define a space therebetween, said plate having openings accepting said shafts;

a single land member integrally formed upon one of said parallel housing and sealing plate faces extending axially in said space toward the other of said parallel faces, said land member extensive through only that portion of the space between said parallel faces adjacent the inlet and shaft openings, said land member and gear cavity wall defining a pressure loading chamber of substantially uniform axial width in the remainder of said space between said parallel faces that is separated from the shaft openings and inlet by said land member;

means communicating outlet pressure to said pressure loading chamber to urge the sealing plate into engagement with the transverse gear faces;

a sealing member in said pressure loading chamber partially encircling said gears and having adjacent right angle faces urged into sealing engagement with said land member and said other of said parallel faces by pressure in said chamber to seal same from the inlet and shaft openings, said sealing member having a groove opening toward the sealing plate;

means in said land member sealing said shaft openings from the inlet;

a second sealing member engaging the sealing plate and cooperating with said first mentioned sealing member to close said groove to form an interior zone; and

elastomer means positioned in said zone for sealing said zone from said pressure loading chamber.

12. The device of claim 11 wherein said sealing plate is provided with an aperture communicating pressure lower than said outlet pressure with said zone.
